P. A. BOWEN,
LASTING MACHINE,
APPLICATION FILED OCT. 28, 1914.

1,223,363.

Patented Apr. 24, 1917.

UNITED STATES PATENT OFFICE.

PHILIP A. BOWEN, OF LYNN, MASSACHUSETTS, ASSIGNOR TO LILLIAN E. LITTLE, OF LYNN, MASSACHUSETTS.

LASTING-MACHINE.

1,223,363.

Specification of Letters Patent. Patented Apr. 24, 1917.

Application filed October 28, 1914. Serial No. 869,115.

To all whom it may concern:

Be it known that I, PHILIP A. BOWEN, of Lynn, in the county of Essex and State of Massachusetts, have invented certain new and useful Improvements in Lasting-Machines, of which the following is a specification.

This invention relates to improvements in machines for lasting shoes and particularly to machines of the type known as "bed" lasting machines in which a last, usually in inverted position, is rested upon a support while the upper materials are worked into lasted position at one or both ends of the shoe by end lasting devices or end lasting mechanisms.

The principal object of the invention is to provide means whereby in lasting machines having features of adjustability hereinafter referred to, the so-called wipers may be evenly, economically and efficiently heated. For convenience in description the invention will be hereinafter described in connection with a lasting machine patented by Matthias Brock, in Patent No. 1,018,477, dated February 27th, 1912, and for the purposes of this specification will be considered as an improvement upon that machine although its more general application will be obvious.

One embodiment of the invention is shown in the accompanying drawings and therein—

Figure 1 is a plan view of a portion of a lasting machine embodying the invention,

Fig. 2 is a corresponding side elevation,

Fig. 3 is a section on the line 3—3 of Fig. 1,

Fig. 4 is a detailed view of the wipers and heating means, and

Fig. 5 is a detailed view of the heating means apart from the lasting machine.

For the purpose of illustrating and describing the present invention, a portion of the lasting machine of Patent No. 1,018,477 is shown herein; only enough of the machine being shown to illustrate the particular subject matter of the present invention. For a complete understanding of the invention it is deemed unnecessary to show certain features of the construction and arrangement of the parts in the patented machine, and accordingly only parts believed to be essential will be hereinafter described. Reference may be had to the above mentioned

patent for a complete showing of the patented machine.

Figs. 1 and 2 of the drawings show the left hand or toe-lasting end of a lasting machine, and therein the toe-lasting mechanism is carried by a bed plate 21, which may be vertically adjustable. A screw 33 provided with a hand wheel is secured to the frame 37 of the toe-lasting mechanism and has screw-threaded engagement with a stationary block 39 on the bed plate for moving the toe-lasting mechanism forwardly and backwardly to position it for lasts of different lengths, the toe rest being moved lengthwise of the shoe with the toe-lasting mechanism by suitable means. A carriage 41 is shown as pivotally connected at 43, with the frame 37 and arranged for lateral movement about its center by means of the screw 47 provided with a hand wheel. The toe-lasting devices are supported on a head which is pivoted at 51 to the carriage 41 and may be adjusted vertically about said pivot by the screw 53, having the hand wheel 55. The lasting devices are carried by a sleeve 57, to which is secured a segment 59 engaged by a screw 61 having a handle 63. By this latter means the toe-lasting devices may be tipped laterally to adapt them to the lateral inclination of the bottom of the shoe. The toe-lasting devices comprise wiper plates 67 removably attached to the carriers 69 and arranged for movement rearwardly and inwardly over the bottom of the toe portion of the last. This movement is effected by connections including the links 71 and equalizing lever 73 with an endwise movable rod 77 to which is connected the hand lever 79.

It is particularly desirable in lasting machines that the wipers be heated to assist in the operation of drawing the upper leather over the toe or heel of the shoe, as the case may be, before it is tacked, wired or otherwise secured in place, preparatory to the final stitching.

The advantages of heated wipers are generally recognized and the difficulties with prior machines have generally been in securing an even and uniform degree of heat in the wipers. It will be readily comprehended that if the wipers are overheated the leather of the shoe will be burned or otherwise disfigured and the shoe injured beyond

repair or the leather permanently weakened. Furthermore in the most efficient lasting machines such as the type of machine herein illustrated, the head of the machine is adjustable in all directions, that is to say, it may be moved toward or from the last support, the wipers may be tilted in the plane of the last or rotated from that plane in order to secure proper adjustment with varying shapes and sizes of lasts. Furthermore it is desirable that the wipers themselves be readily interchangeable so that the machine may be used upon different styles of shoes, a differently formed wiper being required for differently shaped lasts.

The present invention provides means whereby the desired results may be accomplished, such means being herein as follows: A pipe 100 is connected to a suitable source 20 of gas supply by a flexible tube 101, the said pipe 100 being mounted upon the movable head of the lasting machine and extending conveniently through a centrally bored hole 102 in the rod 77. A cock, in the form of a 25 screw 103, is provided to adjust the flow of gas from the source to a pair of burners 104 and 105 formed by a pair of branching tubes 106 and 107. These tubes are so positioned that the flame at the burners 104 and 105 30 is directed toward the underside of the wipers 67 when the wipers are in retracted position. The gas supply is preferably so adjusted that a blue flame is produced at the burners in order that the wipers may not be 35 smutted and thereby soil the leather of the shoe, and the flame is preferably directed outwardly away from the shoe in order that the leather may not be burned or scorched.

It will be apparent that proper adjustment of the flames may be made by the cock 40 103 so that the wipers will be maintained at proper temperature, and the branching tubes 106 and 107 leading from the common supply pipe 100, wherein the cock 103 is located, 45 insure equal heating of both wipers. During the operation of the machine the wipers are normally maintained in retracted position for the greater portion of the time during which the machine is in use, and the 50 arrangement shown will thus insure the

maintenance of a substantially uniform degree of heat in the wipers.

In operation, it is customary to insert a last in the machine, to then adjust the head forward or back as the needs of the moment 55 may require, and to adjust the head in any other direction permitted by the several adjusting means heretofore described. The wipers are then brought forward from the position shown in Fig. 2 by movement of the 60 handle 79. It will be apparent that during the adjustment of the head, the burners are carried with the head and maintained in their predetermined relation with the wipers so that the movement of the head has no 65 effect upon the heating means to destroy the proper relation between the burner and the wiper.

It is of course obvious that the improvement herein shown may be applied to the 70 heel wipers as well as to the toe wipers with equally advantageous results. It should be understood that the invention may be variously modified and embodied within the scope of the subjoined claims. 75

I claim as my invention:

1. The combination with a lasting machine having an adjustable head, of a pair of wipers mounted thereon; means mounted upon said head providing burners for heating said 80 wipers; and means connecting said burners with a source of fuel supply.

2. The combination with a lasting machine having an adjustable head and a fixed base; of means to move said head in a plurality 85 of directions relatively to said base; wipers carried by said head and movable therewith; means providing burners also carried by and movable with said head to maintain said burners in predetermined relation with said 90 wipers when in retracted position to uniformly heat the same; and a flexible connection from said burners to a source of fuel supply therefor.

In testimony whereof I have affixed my 95 signature, in presence of two witnesses.

PHILIP A. BOWEN.

Witnesses:

WILLIAM J. EVERETT,
DANIEL J. D. MORAN.
